[57] CLAIM

The ornamental design for a percutaneous endoscopic gastrostomy tube, as shown and described.

DESCRIPTION

FIG. 1 is a front elevational view of a percutaneous endoscopic gastrostomy tube, showing our new design, the back elevational view being a mirror image thereof; FIG. 2 is a top plan view thereof;

FIG. 3 is a right side elevational view thereof;

FIG. 4 is a bottom plan view thereof;

FIG. 5 is a left side elevational view thereof; and

FIG. 6 is fragmentary cross-sectional view taken along line 6—6 of FIG. 2.
